DUAL VOLTAGE REGULATOR

Merlin Petroff, Round Lake, Ill., assignor to
 Stewart-Warner Corporation, Chicago, Ill., a
 corporation of Virginia

Application June 22, 1949, Serial No. 100,581

4 Claims. (Cl. 307—11)

1

The present invention relates to voltage regulating circuits and has for its purpose to provide simple means for the supply of a high direct current voltage and a relatively low direct current voltage, both with a high degree of regulation and from a single source.

In many electronic devices, two separate direct current voltages are required, both of which should preferably have a high degree of regulation. As an example, some apparatus requires plate voltages in one range and screen voltages in another range with a nice degree of control and regulation of both of these direct current voltages. Ordinary control circuits using cold cathode diodes such as a neon or argon tube are satisfactory for many purposes, but are not capable of giving consistent operations at voltages below that at which current flows through the stabilizing tube.

It is one of the objects of the present invention, therefore, to provide a novel dual voltage stabilizing circuit which supplies one voltage at a high range above that at which the stabilizing glow tube ionizes and the other voltage well below this range.

A further object is to provide a novel circuit which accomplishes the above with a minimum of equipment and with a high degree of stabilization and which has a very low apparent impedance in both power supply circuits.

Other objects and advantages will become apparent from the following description of a preferred embodiment of my invention which is illustrated in the accompanying drawing.

The single figure of the drawing is a diagrammatic representation of one example of a dual voltage regulating circuit embodying the present invention.

Referring to the circuit diagram the specific circuit shown may be considered as supplied with unregulated voltage at about 400 volts D. C. at the terminal 10. The circuit illustrated is for the purpose of supplying from the unregulated 400 volt D. C. source a high range regulated voltage, which in the present instance may be considered as between 175 and 275 volts, and a separate stabilized low range voltage which is adjustable in the present example between 25 and 75 volts, with both of these voltage sources having a low apparent impedance.

In the interest of complete disclosure, specific values will be given for the components in the circuit diagram although it will be appreciated that the circuit shown will operate with a wide variation in these values and with other changes

2

which will be apparent to those skilled in the art. Also, of course, different electronic tubes may be substituted for those shown.

In the specific circuit illustrated, the unregulated voltage source is connected to the terminal 10 which in turn is connected to the plate 12 and screen 14 of a tube 16 which may be considered as of the 7B5 type. The high voltage terminal 10 also is connected through a 27,000 ohm resistor 18 to one of the plates 20 of a dual triode tube 22, such as a 7F7, for instance. The grid 24 of the 7B5 is connected to the cathode 26 by way of a 500,000 ohm resistor 28 and also to the plate 30 of a 7C7 type tube 32. The cathode 26 of the 7B5 is also connected to the regulated high voltage output terminal of the circuit indicated at the point 34. This high voltage line is also connected to ground through a 47,000 ohm resistor 36 in series with a .05 mfd. capacitor 38.

20 The ungrounded side of this capacitor is also connected by a line 40 to the cathode 42 and suppressor grid 44 of the tube 7C7 and also to ground through a one-half watt neon or argon regulating tube 46. The high voltage output terminal 34 is connected through a 27,000 ohm resistor 48 to a junction point 50 which in turn is connected to a 70,000 ohm variable resistor 52 having a slider 54 connected to the grid 56 of the 7C7 and an opposite end 58 which forms a junction 60 with a 5,000 ohm resistor 62 leading to ground. The junction 60 is also connected by a line 64 to one of the cathodes 66 of the dual triode 22. The screen 68 of the 7C7 is connected to the junction 50 between the 26,000 ohm resistor 48 and the 70,000 ohm resistor 52.

35 The grid 70 of the dual triode 22 which is associated with the plate 20 is connected through a 500,000 ohm resistor 72 to the cathode 74 on the same side of the tube and to the output terminal 76 of the low voltage supply. This grid 70 is also connected to the plate 78 on the opposite side of the dual triode 22, this plate 78 being associated with the cathode 66 and with a grid 80 which is connected to the slider 82 of a 20,000 ohm variable resistor 84 connected between the output terminal 76 and ground. All of the heaters in the tubes, indicated by the numeral 86, are energized in the usual manner from a 6 $\frac{1}{2}$ volts filament supply. In this circuit the slider 54 of the variable resistor 52 is used for regulating the high voltage potential at the terminal 34 while the slider 82 of the variable resistor 84 is used similarly for varying the low voltage at the output terminal 76.

50 The circuit operates in the following manner.

The tube 46 is a gaseous voltage regulator which provides across its terminals a constant voltage difference which maintains the potential of the cathode 42 of the amplifier tube 32 at a fixed potential irrespective of the voltage applied to the regulator circuit. The tube 32 is operated as a direct coupled D. C. amplifier, the output of which is applied to the control grid 24 of the tube 16 which determines the output voltage. The control grid 56 of the tube 32 is at a potential which is determined by the setting of the slider 54 and therefore is a definite but variable fraction of the regulated potential between the terminal 34 and ground. Since the resistor 28 in the plate circuit of the tube 32 is large so that the amplification of the grid 56 to cathode 42 voltage is large, it will be seen that as the grid 56 to cathode 42 potential is reduced to less than cutoff to the tube 46 the voltage at the grid 24 is rapidly reduced. This increases the voltage drop across the tube 16 and reduces the output voltage. The output voltage is seen to be very sensitive to the current in the resistor 28 and this current in turn is very sensitive to changes in the difference in the potential from ground to the cathode 42 and the grid 56 of the tube 32 which difference is also sensitive to the output voltage.

An analysis of the above shows that the potential on the grid 56 is less than the reference voltage across the tube 46 by an amount which is almost constant and only slightly less than cutoff for the tube 32. This causes the potential at the terminal 34 to be substantially constant since the ratio of the potential of the grid 56 to the output voltage is determined by the setting of the slider 54.

Anything which tends to change the output voltage, such as a variation in the input voltage at 10 or a variation in the load connected to the terminal 34, changes the grid 56 to cathode 42 potential so as to result in a change in the voltage drop across tube 16 so as to tend to keep the output voltage from changing.

The portion of the circuit below the broken line A—A is used to supply the regulated voltage at low potential. In this portion of the circuit, the upper half of the tube 22, that is, the cathode 74, grid 70 and plate 20, act as a control for the output voltage at 76. In other words, the output low voltage depends upon the voltage drop across this portion of the tube. The grid 70 to cathode 74 potential determines this voltage drop characteristic and the potential of the grid 70 is in turn determined by the amplification of the lower half of the tube. The amplification factor of the lower half of the tube is high because of the high value of the resistor 72 in its plate circuit. Inasmuch as the potential of cathode 66 is fixed as a certain ratio of the regulated high output voltage at the point 34 (because of the fixed voltage divider made up of resistors 48, 52 and 62), the potential of the grid 60 is the determining factor in the low voltage control system. This potential is seen to be a function of the regulated low output voltage at terminal 76, the particular ratio being chosen by positioning the slider 82 as desired. Any tendency of the voltage at terminal 76 to fluctuate for any reason is thus seen to be counteracted by a proper change in the voltage drop across the upper half of the tube so as to return the output voltage to the desired potential. Inasmuch as the regulated voltage for the cathode 66 can be far lower than any reference voltage possible of attainment di-

rectly from a glow tube of the type 46, it is apparent that the regulated output voltage at 76 can be but a small fraction of the regulated voltage at 34 if desired.

Having described my invention in connection with one specific embodiment thereof, it will be apparent that variations may be made therein without departing from the spirit and scope of the invention. The scope of the invention, therefore, is to be measured by the following claims.

I claim:

1. A dual voltage regulating circuit adapted to be connected to a source of high direct current unregulated voltage comprising a high voltage input terminal, a high voltage output terminal, an electron tube connected between said terminals and adapted to vary the voltage drop between said terminals according to the potential upon its grid, an amplifier tube adapted to regulate the potential on said grid, said amplifier tube having a cathode and control grid, a voltage divider connected to said output terminal, a variable tap on said voltage divider connected to said control grid, a cold cathode gaseous tube connected to said cathode to stabilize the potential on said cathode, a second output terminal, an electron tube connected between said input terminal and said second output terminal to vary the voltage at said output terminal according to the voltage drop of the last said electron tube, the last said electron tube having a control grid to vary the voltage drop across the last said electron tube according to the potential on the last said grid, a second amplifier connected to vary the potential on the last said grid, said second amplifier having a control grid, a second voltage divider connected to the last said output terminal, a tap on said second voltage divider connected to the last said grid, and a tap on the first said voltage divider at a potential lower than the potential of the first said tap on the same voltage divider connected to the cathode of said second amplifier.

2. A dual voltage regulating circuit adapted to be connected to a source of high direct current unregulated voltage comprising a high voltage input terminal, a high voltage output terminal, an electron tube connected between said terminals and adapted to vary the voltage drop between said terminals according to the potential upon its grid, an amplifier connected to regulate the potential on said grid, said amplifier having a cathode and control grid, a voltage divider connected to said output terminal, a variable tap on said voltage divider connected to said control grid, means to fix the potential on said cathode, a low voltage output terminal, an electron tube connected between one of said high voltage terminals and said low voltage output terminal to vary the voltage at said low voltage output terminal according to the voltage drop of the last said electron tube, the last said electron tube having a control grid to vary the voltage drop across the last said electron tube according to the potential on the last said grid, a second amplifier connected to vary the potential on the last said grid, said second amplifier having a control grid, a second voltage divider connected to the last said output terminal, a variable tap on said second voltage divider connected to the last said grid, and voltage dividing means connected to the high voltage output terminal to fix the second amplifier cathode at a potential lower than that fixed on the first said amplifier cathode.

3. A dual voltage regulating circuit adapted to

be connected to a source of high direct current unregulated voltage comprising a high voltage input terminal, a high voltage output terminal, an electron tube connected between said terminals and adapted to vary the voltage drop between said terminals according to the potential upon its grid, an amplifier connected to regulate the potential on said grid, said amplifier having a cathode and control grid, a voltage divider connected to said output terminal, a variable tap on said voltage divider connected to said control grid, means to fix the potential on said cathode, a second output terminal, an electron tube connected between one of said high voltage terminals and said second output terminal to vary the voltage at said second output terminal according to the voltage drop of the last said electron tube, the last said electron tube having a control grid to vary the voltage drop across the last said electron tube according to the potential on the last said grid, a second amplifier connected to vary the potential on the last said grid, said second amplifier having a control grid, a second voltage divider connected to the second output terminal, a variable tap on said second voltage divider connected to the last said grid, and means connected to the high voltage output terminal to supply the second amplifier cathode with a fixed potential. 25

4. A dual voltage regulating circuit adapted to be connected to a source of high direct current unregulated voltage comprising a high voltage input terminal, a high voltage output terminal, an electron tube connected between said terminals and adapted to vary the voltage drop between said terminals according to the potential upon its grid, an amplifier connected to regulate the potential on said grid, said amplifier having a cathode and control grid, a voltage divider connected to said output terminal, a variable tap on 35

said voltage divider connected to said control grid, a cold cathode gaseous tube connected to said cathode to fix the potential on said cathode at the voltage breakdown point of said cold cathode tube, a low voltage output terminal, an electron tube connected between said input terminal and said low voltage output terminal to vary the voltage at said low voltage output terminal according to the voltage drop of the last said electron tube, the last said electron tube having a control grid to vary the voltage drop across the last said electron tube according to the potential on the last said grid, a second amplifier connected to vary the potential on the last said grid, said second amplifier having a control grid, a second voltage divider connected to the last said output terminal, a tap on said second voltage divider connected to the last said grid, and means connected to the high voltage output terminal to supply the second amplifier cathode with a fractional portion of the potential at said high voltage output terminal, said fractional portion being smaller than the breakdown potential of said cold cathode tube. 20 15
